US0D1044494S

(12) **United States Design Patent** (10) **Patent No.:** **US D1,044,494 S**
(45) **Date of Patent:** **** Oct. 1, 2024**

(54) **TRAY**

(71) Applicant: **Graphic Packaging International, LLC**, Atlanta, GA (US)

(72) Inventor: **Elliot Hithersay**, Derby (GB)

(73) Assignee: **Graphic Packaging International, LLC**, Atlanta, GA (US)

(**) Term: **15 Years**

(21) Appl. No.: **29/785,897**

(22) Filed: **May 27, 2021**

(51) LOC (14) Cl. **09-03**

(52) U.S. Cl.

USPC **D9/456; D9/433**

(58) **Field of Classification Search**

USPC D9/414, 430, 431, 433, 444-445, 456, D9/711, 715, 718, 721, 748, 418, 427, D9/755, 761, 425; D7/601, 602, 538, D7/540, 550.1; D3/203.5, 202, 207, 210; D4/116

CPC B65D 5/00; B65D 5/0015; B65D 5/0045; B65D 5/13; B65D 5/40; B65D 5/2033; B65D 1/22; B65D 1/225; B65D 1/24; B65D 1/34; B65D 1/38

(57) **CLAIM**

The ornamental design for a tray, as shown and described.

DESCRIPTION

FIG. 1 is a perspective view of a tray showing my new design according to a first embodiment.

FIG. 2 is a left elevation view of the tray of FIG. 1, the right elevation view is a mirror image.

FIG. 3 is a front elevation view of the tray of FIG. 1, the rear elevation view is a mirror image.

FIG. 4 is a top plan view of the tray of FIG. 1.

FIG. 5 is a bottom plan view of the tray of FIG. 1.

FIG. 6 is a plan view of the tray of FIG. 1 in an unfolded configuration

FIG. 7 is a perspective view of a tray showing my new design according to a second embodiment.

FIG. 8 is a left elevation view of the tray of FIG. 7, the right elevation view is a mirror image.

FIG. 9 is a front elevation view of the tray of FIG. 7, the rear elevation view is a mirror image.

FIG. 10 is a top plan view of the tray of FIG. 7.

FIG. 11 is a bottom plan view of the tray of FIG. 7; and, FIG. 12 is a plan view of the tray of FIG. 7 in an unfolded configuration.

All evenly-spaced broken lines represent parts of the tray that do not form part of the claimed design.

1 Claim, 12 Drawing Sheets
